REFRIGERATING SHIPPING CONTAINER

Herbert N. Lapetina, Norfolk, Va.

Application November 1, 1951, Serial No. 254,335

1 Claim. (Cl. 62—91.5)

1

This invention relates to packaging cartons and containers particularly adapted for shipping produce, and in particular a container having means for providing circulation through products therein and also areas at the ends divided off from the interior of the container and providing compartments for ice and the like.

The purpose of this invention is to provide means for obtaining circulation through shipping cartons and containers whereby cool air from ice or Dry Ice positioned in an end of the container is circulated through the interior thereof.

Various types of cartons and containers have been provided for packaging produce such as fruits, vegetables, flowers, and frozen juices, ice cream, fresh shrimp, fish, chicken, turkeys, beef, pork and the like, however, damp air without circulation damages many types of produce and where the products are frozen they are difficult to pack in and remove from cars, trucks and the like. With this thought in mind this invention contemplates a corrugated paper box like carton having transversely disposed spacing trays at the ends and having a longitudinally positioned perforated tube extended through the center.

The object of this invention is, therefore, to provide means for forming a shipping carton whereby circulation is provided through products in the carton.

Another object of the invention is to provide a shipping carton having ventilating means therein that is readily adapted for carrying different types of produce.

A further object of the invention is to provide a shipping carton having ventilating means therein which is of a simple and economical construction.

With these and other objects and advantages in view the invention embodies an elongated carton substantially rectangular shaped in cross section having closed upper and lower ends with an elongated perforated tube extended therethrough and with transversely disposed partitions spaced from the ends.

Other features and advantages of the invention will appear from the following description taken in connection with the drawing wherein:

Figure 1 is a vertical section through the container showing an ice holding tray in the upper end.

Figure 2 is a detail illustrating a perforated tube adapted to be extended through the center of a carton.

Figure 3 is a blank showing a perforated sheet

of material from which the tube shown in Fig. 2 is formed.

Figure 4 is a sectional plan through the carton taken on line 4—4 of Fig. 1.

5 Figure 5 is a plan view showing one of the trays of the container before the flanges at the edges and tube holding tabs at the center are folded to operative position.

10 Figure 6 is a side elevational view of the container showing an inner liner such as is used for frozen produce such as vegetables, fruits, ice cream and the like.

15 Figure 7 is a sectional plan through the container shown in Fig. 6 showing perforations in the trays and circulating channels in the corners.

Figure 8 is a plan view showing a blank from which the trays are formed, being similar to that shown in Fig. 5, and illustrating a modification wherein the trays are formed with perforations 20 and the corners are cut on diagonal lines.

Figure 9 is a detail showing one end of a blank from which the liner of the carton is formed, illustrating the diagonally disposed corners and with parts broken away.

25 Referring now to the drawings wherein like reference characters denote corresponding parts the ventilated refrigerating container of this invention includes a box like casing having side walls 10 and 11, end walls 12 and 13, end flaps 14 and 15, secured by adhesive strips or tapes 16 and 17, respectively, a perforated centrally positioned tube 18, an upper tray 19, spaced from one end of the casing, and a similar tray 20 spaced from the opposite end of the casing.

30 In the design shown in Fig. 1 the trays 19 and 20 are formed with flat pieces of material with flanges 21 at the edges and tabs 22 at the center and, as illustrated in Fig. 1, the tabs 22 extend downwardly providing a center opening 23 in 40 which the end of the tube 18 is positioned.

The flanges 21 are positioned against the inner surfaces of the walls 10, 11, 12, and 13 and with the flanges positioned as shown in Fig. 1 they provide spacing elements spacing the flat base 45 sections of the partitions or trays from the ends of the container.

The flanges 21 of the horizontally disposed trays may be short as shown in the lower end of the container, illustrated in Fig. 1, or long as shown in the upper end of the container, and it will be understood that trays with flanges of the same length may be provided in both ends of the container or any suitable arrangement of 50 the trays may be used as may be required for

the different produce or products carried in the containers.

In this design the center tube 18 is formed from a flat sheet of material 24 with perforations 25 provided in the sheet and tube.

In the design illustrated in Fig. 6 a container 26 similar to the container shown in Fig. 1 is provided with a continuous lining 27 and the lining is formed with diagonally disposed sections 28 at the corners providing open channels 29 to facilitate circulation through the container.

As shown in Fig. 7 the ends of the sheet of material forming the lining 27 are positioned in one of the diagonally disposed corners whereby end flanges 30 and 31 are joined by an adhesive strip 32.

The liner 27 is formed from the blank 33, illustrated in Fig. 9 and the sections of the blank forming the diagonally positioned corners are provided with V-shaped notches 34 in the ends to provide communication between the areas in the channels 29 and interior of the container. The ends 30 and 31 are also provided with diagonally positioned corners 35 for the same purpose.

For this use the carton is provided with trays 36 having flanges 37 on the edges and tabs 38 at the center, similar to the trays 19 and 20, and as shown in the drawing the trays 36 are provided with perforations 39 to facilitate circulation between the end compartments beyond the trays and the intermediate part of the carton or container. The trays 36 are also provided with diagonally disposed corners 40 to correspond with the sections 28.

The container illustrated in Fig. 6 is also provided with a centrally disposed perforated tube 41 corresponding to the tube 18 and with the perforations 42 of the tube coating with the perforations 39 of the trays or pans circulation is provided throughout the interior of the container. By this means cold air from ice positioned in the upper end of the container circulates downwardly through produce in the container and the warmer air throughout the produce passes upwardly through the channels 29 formed in the corners.

It will also be understood that for use for a certain product, such as wet commodities including sea food and particularly fresh shrimp and fish and also for use for shipping chickens, turkeys, beef, pork and other similar products it is desired to coat the inner surface of the container with a lining of paraffin and all products of this type should be frozen before they are placed in the container.

It will also be understood that for use with some products and particularly frozen commodi-

ties the commodities are placed in paper bags or other similar individual containers.

It will be understood that other modifications may be made in the design and arrangement of the parts without departing from the spirit of the invention.

What is claimed is:

In a shipping container, an elongated box like casing, said casing being rectangular in cross section and having two pairs of spaced parallel side walls interconnected together, and spaced parallel end walls formed from flaps hingedly connected to the ends of the side walls, means for securing the flaps in place, a continuous liner arranged in said casing and positioned contiguous to the inner surface of said side walls, said liner being provided with diagonally disposed sections at its corners providing open channels for the circulation therethrough of air, the ends of the liner abutting each other in one of the diagonally disposed sections thereof, means securing the abutting ends of the liner together, the ends of the diagonally disposed sections being provided with notches, an upper tray having flanges on its edges positioned in the casing in spaced parallel relation with the end walls, the flanges of said tray being arranged contiguous to the inner surface of said liner and extending between said tray and the upper wall, a second tray arranged in spaced parallel relation with and below said first tray, said second tray having flanges arranged contiguous to the inner surface of said liner and extending between said second tray and the lowest end wall, said trays having the same area as the inside cross sectional area of said liner, said trays being provided with centrally positioned registering openings and with perforations, a tube extending from the upper end wall to the lower end wall through said openings and being provided with perforations throughout its length, tabs extending outwardly from said trays and surrounding said tube, the area between said first tray and the upper end wall providing a storage chamber for refrigerant, said notches and perforations in said tube providing communication between the refrigerant and all parts of the container.
